UNITED STATES PATENT OFFICE.

SIGMUND V. HUBER, OF PITTSBURG, PENNSYLVANIA.

FEED-TABLE FOR ROLLING-MILLS.

No. 857,282.

Specification of Letters Patent.

Patented June 18, 1907.

Application filed February 3, 1905. Serial No. 244,020.

To all whom it may concern:

Be it known that I, SIGMUND V. HUBER, residing at Pittsburg, in the county of Allegheny and State of Pennsylvania, a citizen of the United States, have invented or discovered certain new and useful Improvements in Feed-Tables for Rolling-Mills, of which improvements the following is a specification.

In operating three high mills it is frequently desirable that the piece should pass back and forth through the same passes, *i. e.* upper and lower, two or more times and it is also desirable in some cases that in lieu of feeding the article transversely to the next adjacent pass to skip one or more passes and to feed the article into the second or third pass along the rolls. In Letters Patent No. 751,733 granted to me February 9th, 1904, I have described and claimed certain improvements in feed mechanisms for mills in which a transverse movement of the article on the feed table is effected by means operative by the feed table itself in its vertical movement. In this patent no provision is made whereby an article can be passed several times through passes in the same vertical plane or whereby the article may be shifted from one pass to the second or third pass along the rolls.

The invention described herein has for its object a construction of mechanism for the transverse shifting of the articles on the tables so constructed and arranged that the article may remain on the table without lateral movement during the vertical movements of the table or may be shifted to any desired extent transversely with the table during the movement of the latter.

The invention is hereinafter more fully described and claimed.

In the accompanying drawings forming a part of this specification Figure 1 is a top plan view of a feed table having my improvements applied thereto. Fig. 2 is an end elevation of the same. Fig. 3 is a sectional detailed view, the plane of section being indicated by the line III—III Fig. 1. Fig. 4 is a sectional detailed view on a plane indicated by the line IV—IV Fig. 3. Fig. 5 is a view partly in elevation and partly in section illustrating a modification of my improvement. Figs. 6 and 7 are diagrammatic views showing passes in rolls and the movements of the article on the feed tables in connection with said passes.

In the practice of my invention the feed

table is arranged to move vertically either as a whole or at one end. In the construction shown the whole table is designed to move vertically in suitable guides 1 and 2. The guides 1 at the rear end of the table being constructed to prevent both the lateral and longitudinal movement of the table while the guides 2, which are generally secured to the housings of the rolls, are adapted to prevent the lateral movement of the table. The table is provided with a series of positively driven feed rollers 3 operated in any suitable manner such for example as an electric motor 4 connected by a suitable train of gearing to a longitudinal shaft 5, provided with bevelled gears intermeshing with correspondingly shaped gears on the feed rollers. Any suitable means may be employed for raising and lowering the table, such for example as that shown consisting of shafts 6 provided with arms 7 connected to the table by adjustable pitmen 8. These shafts are also provided with arms 9, connected as shown to a fluid pressure cylinder 10. By the operation of this fluid pressure cylinder the shafts are rotated and the desired vertical movement is imparted to the table. In order to shift the articles laterally across the table, ribs or guide plates 11 are adjustably secured to slides 12 which are mounted in suitable guideways 13, as clearly shown in Figs. 1 and 4 arranged transversely of the table. The adjustability of the ribs can be attained in any suitable manner, as for example by slotting the slides 12 and securing the ribs to the slides by bolts passing through the slots.

The slides 12 are connected by rods 14 to arms 15 on a shaft 16, and to this shaft is also secured another arm 17, which has an adjustable connection to a stationary abutment, as shown in Figs. 2 and 5. In Fig. 2 the connection of this arm 17 to the abutment 18 is formed by threaded rods and turnbuckle 19, such connection having its ends pivotally connected to the slide 20 on the arm 17, and to a movable link 21, provided with an angular slot for the reception of the abutment 18. It will be readily understood that when the abutment is in the horizontal portion of the slot in the link, a vertical movement of the table will cause a rotation of the shaft 16 and a consequent shifting of the slides 13, as the shaft is carried by the table but the arm 17 thereon is prevented from movement and hence a rotation of the shaft is effected. By adjusting the length of

the turn-buckle connection between the slide 20 and the link and adjusting the slide 20 by a screw operated by a hand-wheel as shown, along the arm any desired transverse movement of the slides will be effected by the regular vertical movement of the table. The link 21 is shifted on the abutment 18, by a lever 22 connected to the link by a rod 23. If no transverse movement of the slides is desired as when the piece being rolled is to be fed back and forth through the same passes as *a* in Fig. 7 a number of times, the link is shifted so that the abutment will lie in the vertical portion thereof. When the abutment is in this position and the table is moved vertically, the link will slide up and down along the abutment and no movement will be imparted to the shaft or the slides.

In lieu of the construction shown in Fig. 2, that shown in Fig. 5 may be employed. In this construction a block 24 is pivotally connected to the end of the arm 17 and arranged to move in guides along a swinging arm or link 25. This arm or link 25 is pivoted as shown at its lower end to a stationary part or abutment of the machine and connected to an operating lever 22 by a rod 23. When the arm or link is in the position shown no movement will be imparted to the slides 12, on the vertical movement of the table, but if the arm or link be shifted to the right a vertical movement of the table will cause such reduced movement of the block along the link as to impart the desired transverse movements of the slides 12.

It is sometimes desirable as before stated to skip one or more passes along the rolls, and hence provision must be made for a greater movement of some of the guide ribs than of the others. To this end the slides 12 are made in sections as clearly shown in Figs. 2 and 3. When the orderly movement of the articles from pass to pass is desired as illustrated in the diagrammatic view Fig. 7 these sections or series of slides are connected by a link 27 in such manner that both sections will be moved together. If however it is desired that some of the articles being rolled shall be moved a greater distance transversely than other articles at the same time passing through the mill, the main sections 12 are connected to the other sections 12^a in such manner that the main sections will have a considerable movement independent of the sections 12^a. A desirable construction to this end consists in connecting the two sections by means of links 28, having slots therein of a length equal to the distance which it is desired that the main section shall move independent of the sections 12^a, as shown in Fig. 3. When thus connected the section would have transverse movements such as indicated in Fig. 6, the sections 13^a moving transversely from the planes of passes *a* to plane of passes *b*, where-

as the sections 12 will move from the plane of passes *b* to the plane of passes *d*, skipping passes *c*.

It is characteristic of my improvement that by shifting a part or member of the connection from the table to the abutment, as the part or member 21 or 25, the guides on the table will either remain stationary or move transversely of the table when the latter is moved up and down. And further it is characteristic of the construction shown in Fig. 5 that the movement of the guides transverse of the table can be varied at any time without varying the vertical movement of the table.

I claim herein as my invention

1. A feed table for rolling mills having in combination means for guiding or directing an article along the table, means for raising and lowering the table, mechanism operative by the table for shifting the guides laterally and means for rendering the shifting mechanism inoperative during the movements of the table, substantially as set forth.

2. A feed table for rolling mills having in combination means for guiding or directing an article along the table, means for raising and lowering the table, mechanism operative by the table for shifting the guides laterally, an arm forming a part of the guide-shifting mechanism, a stationary abutment, and connection from the abutment to said arm consisting of parts or members, one movable relative to the other and means for shifting one of said parts or elements to a position to control the position of the arm.

3. A feed table for rolling mills having in combination two or more series of slides arranged to move transversely of the table, guides carried by the slides means for raising and lowering the table and mechanism operative by the table for shifting one series of slides independent of the other series, substantially as set forth.

4. A feed table for rolling mills having in combination two or more series of slides arranged to move transversely of the table, guides carried by said slides, means for raising and lowering the table and mechanism operative by the table for shifting one series of slides a greater distance than the other series of slides, substantially as set forth.

5. A feed table for rolling mills having in combination means for guiding or directing the articles along the table, means for raising and lowering the table, a link having a fixed pivotal point, a connection from said link to the guiding means, said connection being movably attached to the link, and means for shifting the link to vary the point of attachment of the connection thereto during the operation of the mechanism.

6. A feed table for rolling mills having in combination means for guiding or directing articles along the table, means for raising and

lowering the table, an arm connected to the guiding means and forming a portion of the guide-shifting mechanism, a link having a fixed pivotal support, a block, a connection from said block to the arm of the shifting mechanism and means for shifting the link during the operation of the feed table, said parts being operative by the table to shift the guides.

10 7. A feed table for rolling mills having in combination means for guiding and directing the articles along the table, means for raising and lowering the table, an arm connected to the guiding means and forming a portion of the guide-shifting mechanism, two parts or elements, one fixed as against movement by the table, and the other movable relative to the first part or element, a connection from one of the elements to the arms of the shift-

ing mechanism and means for shifting one of the elements during the operation of the feed table.

15 8. A feed table for rolling mills having in combination means for guiding or directing articles along the table, means for raising and lowering the table, and connections from the guiding means to a stationary abutment, said connection including a movable part or element and means whereby said movable part or element may be shifted during the operation of the table.

In testimony whereof, I have hereunto set my hand.

SIGMUND V. HUBER.
